UNITED STATES PATENT OFFICE.

JOHN W. CHAMBERS, OF MIDDLETON, MICHIGAN.

COLLAPSIBLE MOLD.

1,113,753.

Specification of Letters Patent.

Patented Oct. 13, 1914.

Application filed April 30, 1913. Serial No. 764,596.

To all whom it may concern:

Be it known that I, JOHN W. CHAMBERS, citizen of the United States, residing at Middleton, in the county of Gratiot and State of Michigan, have invented certain new and useful Improvements in Collapsible Molds, of which the following is a specification.

This invention relates to an improved bridge-form, and more particularly to a collapsible mold adapted and intended to be used for excavating purposes such as culvert, sewer and tunnel construction.

An object of the invention is to provide simple and efficient means for expanding or collapsing the outer shell of the mold in such a novel and peculiar manner that it may be easily withdrawn when the structure in connection with which it is used, is completed.

A still further object of the invention contemplates the provision of a specially devised form adapted to be arranged upon the interior of the shell, and operated from the exterior thereof, for enlarging or diminishing the size of the mold as occasion demands.

The invention still further resides in the provision of a plurality of detachable plate members adapted to be employed in connection with the invention for effecting a substantially cylindrical mold form capable of limited adjustment, the said adjustment being accomplished by the operation of a suitable wheel forming a part of the interior frame mechanism, thus permitting the mold to be collapsed and quickly and readily withdrawn from the structure after the walls thereof have become sufficiently hardened to remain intact.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an elevation of a collapsible mold constructed in accordance with my invention; Fig. 2 is an end view; Fig. 3 is a longitudinal sectional view; Fig. 4 is a cross sectional view; Fig. 5 is an enlarged sectional view illustrating the manner in which

the plate members are retained upon the collapsible frame. Fig. 6 is a detail perspective view of one of the plate fastening members; and Fig. 7 is a cross-sectional view of the inner plates showing their use as a mold without the outer member.

Referring now to the drawings, wherein is illustrated the preferred form of my invention the numeral 1 designates a plurality of (preferably four) curved sheet metal plates, which are adapted to form when the frame work upon which they are arranged is collapsed, a substantially cylindrical mold, the said plates being supported through the medium of a plurality of arms 2 radiating from a suitable hub 3 slidably mounted upon a concentrically disposed shaft 4 which extends throughout the length of the mold. The arms 2 are pivotally connected as at 5 to suitable brackets 6 which are in turn permanently secured to the inner face of the plates 1, the opposite end of the said arms being pivotally secured as at 7 to ears 8 formed integrally with and projecting from the periphery of the hub 3 so as to allow the said shaft to be laterally slid or moved independent of like movement on the part of the plates 1.

One end of the shaft 4, the said shaft being hollowed, is provided with a cap 9, the said cap being threaded upon the said shaft and having a central bore 10 formed therein through which an exteriorly screw threaded rod 11 extends. The opposite end of the rod 11 from that projecting into the hollow shaft 4 has keyed or otherwise secured thereto a hand wheel 12 for the purpose of rotating the screw rod 11 for increasing or diminishing the size of the mold form in a manner to be hereinafter fully described. A collar 13 is loosely mounted upon the rod 11 adjacent the handle 12, the said collar being held against lateral movement upon the said rod through the medium of an annular flange 14 formed integrally with the said rod. Connecting rods 15 radiate from the collar 13 to which they are pivotally secured as at 16 and extend to suitable brackets 17 secured to the inner face of the plate members 1 near one extremity of the mold where they are pivotally secured as at 18. Any suitable means such as a turn buckle 18' may be arranged upon the rods 15 for adjusting the length thereof as occasion demands.

By operating the hand wheel 12 in one

- direction it will be seen that the shaft 4 is laterally moved toward the said wheel while the plate members 1 are likewise moved in a direction opposite to that of the said shaft 4, thereby collapsing or decreasing the size of the mold form and bringing the several plates into closer proximity by reason of the pivotally connected arms 2 comprising a part of the operating means.
10. Lateral movement of the collar 13 is prevented by reason of the annular flange 14, this construction causing the rods 15 to impart lateral movement to the plates 1 according to the rotation of the hand wheel 12.
15. Any number of molds constructed as above described may be operated by one and the same hand wheel by connecting the central shaft thereof to the hollow shaft 4 as is shown at 19 in the drawings.
20. Detachable plate members 20 are employed in connection with the invention when a complete cylindrical outer shell is desired, the said plates being arranged upon the outer face of the plate members 1 where 25 they are supported by means of suitable fastening members 21, the said members being substantially T-shaped in elevation, the cross head 22 extending transversely of an elongated aperture or slot 23 formed within 30 the said detachable plates 20. The vertically extending portion 24 of the fastening member is adapted to extend through the said slots 23 of the plates 20 and through an opening 25 of the plate members 1 where 35 it is effectually retained by means of a nut 26 threaded upon the said portion 24 from the inner face of the said plate member 1. Retainers 27 are secured to certain of the plates 20 for the purpose of retaining other of the 40 said plates against lateral movement during adjustment of the mold form, the said retainers adapted to overlap one edge of certain of the plates as is clearly shown in Fig. 4 of the drawings. Where the metallic 45 plates 20 are employed, and it is desired, that the mold form should be either increased or diminished in size it will be seen that the slots 23 of the said plates will permit limited adjustment of the said form, 50 such adjustment being accomplished by the operation of the hand wheel 12 above described.
- The retainers 27 prevent lateral movement of the plates 20 in one direction and 55 thereby force the overlapping end of the said plates to laterally move during adjustment of the form, the fastening members 21 supporting the overlapping ends of the plates in the desired manner.
60. It will be seen from the above, taken in connection with the accompanying drawings that complete adjustment of the mold form is controlled by the operation of the hand wheel 12, the said wheel being mounted 65 upon the exterior of the said form; that by
- the provision of the pivoted arms 2, the said form may be either increased or diminished in size as occasion demands; and that by providing metallic plates of various sizes, complete cylindrical outer shells of various sizes may be effected by the operation of the hand wheel 12 in the manner above described.
- In reduction to practice, I have found that the form of my invention, illustrated 75 in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages 80 of my invention, as defined in the appended claims.
- Having thus fully described my invention, what I claim as new and desire to secure by Letters Patent, is:—
1. A collapsible mold including an inner shell composed of a plurality of normally spaced segmental plates, an outer shell composed of a like number of overlapping plates, means rigid with said segmental plates and slidably engaging said overlapping plates to maintain the latter adjustable thereupon, and means engageable with said segmental plates for adjusting said overlapping plates to increase and diminish the size of the mold.
2. A collapsible mold including an inner expandible shell, an outer expandible shell, means rigid with said inner shell and slidably engageable with said outer shell to maintain said outer shell thereupon, and means operable within the inner shell for expanding or contracting the mold.
3. A collapsible mold including an inner expandible shell, an outer shell composed of a plurality of shell sections, the said sections being disposed to overlap one another, certain of the said shell sections having aligned slots formed therein, means rigid with said inner shell and working within said slots to provide for the lateral adjustment of said outer shell sections, and means carried by certain of said sections and engageable with other of said shell sections to maintain the said sections incapable of outward separation, as and for the purpose set forth.
4. A collapsible mold including an inner shell composed of a plurality of shell sections, an outer shell composed of a like number of shell sections, said outer shell sections being disposed to overlap one another, certain of the said outer shell sections having aligned slots formed therein, means carried by certain of said outer shell

sections adapted for engagement with other of said outer shell sections to maintain the said sections incapable of outward separation, and a removable fastening member rigid 5 with said inner shell and working within said slots of said outer shell to maintain the latter upon said inner shell incapable of outward separation, and means operable within the inner shell and engageable with 10 the said inner shell sections for adjusting said outer shell sections laterally to increase and diminish the size of the mold.

5. A collapsible mold including an inner expandible shell, an outer expandible shell, 15 means connecting the said two shells to ex-

pand the latter according to the expansion of the former, an operating screw mounted concentrically within the said inner shell, screw arms connecting the said screw to the said inner shell, and turn-buckles operable 20 upon the said arms the screw and arms providing for the expansion of said inner shell, as and for the purpose set forth.

In testimony whereof I affix my signature in presence of two witnesses.

JOHN W. CHAMBERS.
